Fig. 5.

This technical drawing illustrates a cross-section of a curved roof system. The roof is supported by a central vertical column and features a curved, ribbed underside. The drawing labels various components: 12, 30, 31, 32, 33, 34, 35, 36, 37, 38, 39, 40, 41, 42, 43, 44, and 45. Labels 30 through 45 are positioned along the right side of the central column, while 12, 35, and 40 are located on the left side. The base of the structure is supported by a series of horizontal beams and brackets.

Fig 6. 47

A technical line drawing of a mechanical assembly. A central vertical rod, labeled 71, passes through a rectangular frame. At the top of the frame, there is a horizontal beam with a slot. A gear assembly, consisting of a larger gear 72 and a smaller gear 73 meshed together, is mounted on the central rod. A cylindrical component 56 is attached to the top of the central rod. The frame is supported by four vertical legs, each with a circular base. The drawing uses dashed lines to indicate hidden parts of the frame and legs. Various parts are labeled with numbers: 71, 72, 73, 56, 25, 74, 75, 76, 77, and 78. The labels are placed near their respective parts, with some like 75 appearing twice.

Fig. 10.

A cross-sectional view of a door assembly. The diagram shows a vertical door frame with various internal components. Labels point to parts such as 81 (top hinge), 82 (bottom hinge), 83 (bottom hinge support), 84 (bottom hinge pin), 85 (bottom hinge support), 86 (vertical door frame), 87 (horizontal door frame), 88 (hinge pin), 89 (hinge support), 90 (hinge pin), 91 (hinge support), 92 (hinge pin), 93 (vertical door frame), 94 (horizontal door frame), 95 (hinge pin), 96 (hinge support), 97 (hinge pin), 98 (hinge support), and 99 (hinge pin). A handwritten label '11' is present near the bottom right.

UNITED STATES PATENT OFFICE.

JAMES CREAR, OF CHICAGO, ILLINOIS.

LOCOMOTIVE.

1,264,020.

Specification of Letters Patent. Patented Apr. 23, 1918.

Application filed August 21, 1917. Serial No. 187,363.

To all whom it may concern:

Be it known that I, JAMES CREAR, a citizen of the United States, residing at Chicago, in the county of Cook and State of Illinois, have invented certain new and useful Improvements in Locomotives; and I do hereby declare the following to be a full, clear, and exact description of the invention, such as will enable others skilled in the art to which it appertains to make and use the same.

This invention relates to improvements in locomotives and has for one of its objects to provide a power operated changeable speed drive gear, whereby greater speed may be obtained without increasing the speed of the engine pistons.

Another object is the provision of a flexible frame structure permitting a wide range of movement of the axles of the supporting and driving wheels, enabling the locomotive to take sharp turns at a high speed without danger of the wheels becoming derailed.

Another object is the provision of means for resiliently and movably supporting the boiler in position above the front and rear trucks so as to permit of independent movement of the latter, as in rounding curves.

A still further object is the provision of a locomotive equipped with an apparatus for generating an electrical current for utilization in connection with electrically operated signaling systems.

A still further object of the invention is to generally improve the construction of locomotives so that greater speed may be obtained with safety to the train and its occupants during travel.

With these and other objects in view, the invention consists in the novel construction, combination and arrangement of parts as will be hereinafter specifically described, claimed and illustrated in the accompanying drawings, in which:

Figure 1 represents a side elevation of the improved locomotive,

Fig. 2 represents a plan view of the rear truck, the boiler and cab being removed,

Fig. 3 represents a bottom plan view of the rear truck,

Fig. 4 represents a vertical sectional view on the line 4-4 of Fig. 2,

Fig. 5 represents a detail sectional view on the line 5-5 of Fig. 2,

Fig. 6 represents a plan view, partly broken away, of the clutch actuating devices for the slow speed gear,

Fig. 7 represents a fragmentary side elevation of the slow speed gear,

Fig. 8 represents a side elevation of the high speed gear,

Fig. 9 represents an enlarged vertical sectional view approximately in the plane of the section line 5-5 of Fig. 2, showing the resilient support for the boiler in detail,

Fig. 10 represents a fragmentary sectional view through the rear portion of the rear locomotive truck, illustrating the yieldable support for the rear drive wheels in detail, and

Fig. 11 represents a vertical sectional view on the line 11-11 of Fig. 10.

Referring to the drawings in detail, wherein similar reference numerals designate corresponding parts throughout the several views, the numerals 15 and 16 designate the front and rear trucks, respectively, upon which the boiler 17 is supported. The boiler is provided with an engineer's cab 18, and is provided at its front end with depending supports 19, which are pivotally mounted on a vertical axis in the frame 16 of the front truck 15.

The relatively narrow main supporting frame 20 of the rear truck 16 is provided with a forwardly directed coupling rod 21, which is pivotally connected at 22 with a rearwardly directed coupling rod 23 carried by the frame 16 of the front truck, whereby the two trucks are pivotally connected and capable of independent movement.

Front and rear drive axles 24 and 25, respectively, are rotatably supported in journal boxes provided upon the main supporting frame 20, and the axles are provided with flanged drive wheels 26 and 27, respectively.

A supplemental frame structure consisting of side and end members 28 and 29, respectively, is supported upon and projects laterally of the main frame 20, and a platform 30 is supported upon the forward portion of the latter. The longitudinal members of the frame 20 are connected intermediate their ends by the spaced transverse connecting members 31, which coöperate with the side members of the frame 20 to provide a housing slidably supporting a vertically movable support 32. Springs 33 are arranged upon the bottom 34 of the guide or housing 31 and normally retain the support 32 in elevated position. The lower part of a circular casing 35 is secured upon

the support 32 and is provided with a plurality of spaced upstanding circular flanges 36, which are telescopically received in the depending flanges 37 of the top casing part 38. A curved boiler support 39 is mounted upon the top casing part 38 and the latter is adapted to oscillate upon the bottom part 35 to permit the boiler 17 to swing relatively to the rear truck 16. The weight of the boiler and engineer's cab 18 are resiliently supported upon the springs 33. The annular chamber 40 between the flanges of the casing parts 35 and 38 is connected by a steam pipe 41 with the steam dome 42 of the locomotive, while the outer annular chamber 43 is connected with an exhaust pipe 44, which is extended forwardly underneath the boiler 17 and through the bottom of the latter into the smoke box, in the usual manner.

Steam engine cylinders 46 are suspended from the front portion of the side members 28 of the supplemental frame structure and each cylinder is connected by a steam pipe 47 with the steam chamber 40, and by an exhaust pipe 48 with the chamber 43. Preferred types of throttle valves and reversing gear for the engine cylinders 46 (not shown) are provided and are operable by the engineer in the cab 18, as usual.

The engine shaft 49 is journaled in the main frame 20 rearwardly of the cylinders 46 and is provided with wheels carrying crank pins 50, which are connected by connecting rods 51 with the piston rods 52.

The outer ends of the shaft 49 at points adjacent the wheels carrying the crank pin 50 are provided with non-rotatable gear wheels 50, which mesh with relatively small pinions 51 slidably and rotatably mounted upon a shaft 52, which latter is rotatably supported in a horizontal position in bearings 53, provided upon the frame 28-29. The shaft 52 is provided with non-rotatable gear wheels 54, which are in permanent mesh with a train of gears 55, having connection with the pinion 56 secured upon the rear drive shaft 25, whereby the rotary movement of the shaft 52 is transmitted to the rear drive wheels 27. The several gear wheels 50, 54, 55 and 56 are so arranged and proportioned as to rotate the rear drive axle 25 at a considerably greater speed than that of the engine shaft 49, and for this reason these wheels will be hereinafter referred to as the high speed gear.

The gear wheels or pinions 51 are rotatably and non-slidably mounted in rectangular frames 58, which latter are slidably mounted upon the shaft 52 and in guides 59 secured to the supplemental frame 28-29. As the frames 58 are moved inwardly upon the shaft 52, the pinions 51 are moved inwardly and are engaged with pins 60 secured diametrically through the end portions 63 of the shaft 62, and said pins are adapted

to be received in diametrical slots formed in the adjacent side faces of the pinions, whereby a non-rotatable connection between said pinions and the shaft is established so as to provide a driving connection between 70 the relatively large gear wheels 50 and the shaft 52.

The inner members of the rectangular frames 58 are provided with inwardly directed extensions 61, which are pivotally connected with one end of a pair of bell cranks 62, pivotally secured at 63 upon the platform 30 and having pivotal connection at their opposite ends with a rod 64 actuated by a piston 65, reciprocably mounted in a cylinder 66. The piston 65 is preferably actuated by air, which is admitted to the cylinder 66 through a valve (not shown) controlled by the engineer of the locomotive, whereby the gear wheels 51 may be moved 85 into and out of engagement with the pins 60, as desired.

Relatively small gear wheels 68 are non-rotatably secured upon the engine shaft 49 inwardly of the gear wheels 50 and mesh 90 with an intermediate gear wheel 69, which latter meshes with a gear wheel 70 of approximately the same diameter as the gear wheel 60, which is secured upon the rear drive shaft 25. The gear wheels 68, 69 and 95 70 are so arranged and proportioned as to drive the shaft 25 at approximately the same rate of speed as the engine shaft 49 and consequently these wheels will be hereinafter referred to as the slow speed gear. 100

The gear wheels 70 are rotatably mounted upon the rear axle 25 and are also non-slidably and rotatably mounted in frames 71, which latter are slidably supported in the frame structure 20. The inner surfaces of 105 the gear wheels 70 are provided with diametrical slots 72, adapted, when the gear wheels are moved inwardly by the frames 71, to receive pins 73 secured diametrically through the axle 25, whereby the gear 110 wheels are non-rotatably connected therewith. The frames 71 are actuated by a rod 74 and bell cranks 75, which are identical in construction to and operated by the same means as the corresponding parts 64 and 62, 115 which actuate the frames 58.

The front drive axle 24 is non-slidably and rotatably mounted in a box 76 supported in the front portion of the main frame 20, and the opposite ends thereof are bifurcated 120 and pivotally receive knuckle rods 77, having angularly directed ends 78 pivotally secured in bifurcated lateral extensions 79 carried by the front drive wheels 26. The angular terminals 78 of the knuckle rods 125 are pivotally secured at 80 between the bifurcations of the extensions 79 and the pivotal connections between the knuckle rod 77 and the front axle 24 and between the knuckle rod 77 and the bifurcated extensions 130

79 are disposed at right angles to each other so as to permit the front drive wheels to move into various angular positions with relation to the shaft 24.

5 The inner portions of the front drive wheels 26 are provided with circumferential flanges 81, received in hook-shaped retainers 82 carried by vertically disposed frames 83.

The frames 83 and front drive wheels 26 10 are movable independently of the main and supplemental frames 20 and 28 and the upper and lower horizontal members of the frames 83 are maintained in parallel relation by a series of parallel rods 85, which 15 extend through the frame 20.

The front drive wheels 26 are provided with laterally projecting crank pins 86, which are pivotally connected with the front ends of the front sections 87 of the connecting rods, which connect the front and rear 20 drive wheels. The rear terminals of the connecting rod sections 87 are pivotally connected by horizontally disposed pivot pins 88 with couplings 89, and each pin 88 is 25 received within a vertical slot 90 formed in a horizontally movable cross head 91, carrying plungers 92 which are received within cylinders or tubular members 93 carried by the frame 83. The movement of 30 the coupling member 89 is guided by the cross head 91, plungers 92 and cylinders 93, in order that the front connecting rod sections 83 will be maintained in properly spaced relation to the front drive wheels 26 35 regardless of the position of the latter with relation to the main frame 20 of the locomotive.

The rear terminals of the coupling members 8 and 9 are pivotally and slidably connected with the slotted forward terminals of the rear connecting rod sections 95 by 40 wrist pins 96, which are adapted to move in the slotted terminals of the connecting rod sections 95 to accommodate the movement of the wheels 26 with relation to the 45 wheels 27 when the locomotive is turning a sharp curve in the track.

The front portion of the rear connecting rod section 95 is connected with the cross head 97, which is slidably supported in guides 98, and the rear terminal of the connecting rod sections 95 are connected with the crank pins 99 of the rear drive wheels 27. A brake cylinder 100 is supported upon 55 the platform 30 and the piston actuated rod 101 thereof is connected with a brake actuating rod 102, which latter extends transversely across the platform 30 and is connected at its opposite terminals with the longitudinally extending rods 103. The rear 60 terminals of the rods 103 are pivotally connected at 104 to a brake rod 106, which latter is pivotally secured at 107 to the frame 28-29. A brake shoe 108 is pivotally secured at 109 to the rod 106 and during the

forward movement of the latter is applied to the rear drive wheel 27. Front brake shoes 110 are pivotally secured to the frame 28-29, and are pivotally secured at 111 to a horizontally disposed rod 112, having 70 connection with the lower terminal of the rod 106, whereby the shoe 110 is applied to the wheel 27 simultaneously with the shoe 108.

The brake cylinder 100 is supplied with 75 compressed air from a cylinder 113 supported upon the platform 30 and is controlled in its operation by the usual engineer's valve (not shown). Air is supplied to the tank 113 by a compressor (not shown) 80 and the air is also utilized to operate an air motor 114, the piston 115 of which is connected with an electric generator 116 adapted to supply an electrical current for the operation of electrically operated signals 85 and any other electrical devices pertaining to train service.

Rail-engaging rollers 117 are rotatably supported on hinged supporting rods 118 depending from the frame 28-29 and are 90 adapted to engage the web of the rails underneath the head to maintain the driving wheels 26 and 27 in engagement therewith.

A guard or fender 119, preferably of hollow construction, is supported by the frame 95 16 of the front truck 15 and is connected with the steam pipe 41 by a flexible connecting element 120, whereby the fender 119 is maintained in a heated condition to prevent 100 the accumulation of snow and ice thereon.

What I claim is:

1. In a locomotive, a truck, drive wheels supporting said truck, driving engines supported by the truck, a changeable speed 105 gear connecting the engine with the drive wheels, and fluid operated means controlling the changeable speed gear.

2. In a locomotive, a truck, drive wheels supporting the truck, driving engines supported by the truck, a slow speed gear connecting the engine with the wheels, said slow speed gear including a clutch for disconnecting the drive wheels from the engine, fluid operated means for actuating the 110 clutch, a high speed gear connecting the engine with the drive wheels and including a clutch, and fluid operated means independent of the first fluid operated means for controlling the second-mentioned clutch. 115

3. In a locomotive, a truck, front and rear axles supported in the truck, rear drive wheels secured to the rear axle, front drive wheels, and means loosely connecting the front drive wheels with the front axle to 120 permit the front drive wheels to move into various angular positions with relation to the rear drive wheels.

4. In a locomotive, a flexible truck structure, drive wheels supported in the front 125

- and rear portions of the truck structure, drive wheels connected with the rear axle, front drive wheels, and means loosely connecting the front drive wheels with the 5 front axle to permit the front drive wheels to move into various angular positions with relation to the rear drive wheels.
5. In a locomotive, a truck, front and rear axles supported in the truck, drive 10 wheels carried by the front and rear axles, said front wheels being movable with relation to the rear wheels, and flexible driving connections between the front and rear drive wheels.
15. 6. In a locomotive, a truck, axles supported in the front and rear portions of the truck, front drive wheels pivotally connected with the terminals of the front axle, rear drive wheels rigidly secured to the rear 20 axle, means for maintaining the front wheels in parallel relation to each other, and flexible driving connections between the front and rear wheels.
7. In a locomotive, front and rear trucks, 25 wheels supporting said trucks, a boiler, means pivotally supporting the boiler upon the front truck, a hollow casing pivotally supporting the rear portion of the boiler on the other truck, a partition arranged in the 30 casing dividing the interior of the latter into live and exhaust steam chambers, an engine connected with the wheels, a steam pipe connecting the live steam chamber of the casing with the engine, means connecting the live steam chamber of the casing with the boiler, and exhaust pipes connecting the 35 exhaust steam chambers of the casing with the engine and with the smoke box of the boiler.
40. 8. In a locomotive, front and rear trucks, wheels supporting said trucks, a boiler, means pivotally supporting the front end of the boiler on one of the trucks, a two-part casing carried partly by the rear portion of the boiler and partly by the rear 45 truck and pivotally supporting the rear portion of the boiler, said casing being of hollow formation, partitions arranged in the casing dividing the interior of the latter 50 into annular live and exhaust steam chambers, pipes connecting the live and exhaust steam chambers of the casing with the boiler, an engine connected with the wheels, and pipe connections between the live and 55 exhaust steam chambers and the engine.
9. In a locomotive, a truck, rear drive wheels therefor, front drive wheels, means movably connecting the truck with the front 60 wheels and permitting swinging movement of the latter on vertical axes, pivotally connected rod sections connecting the front and rear drive wheels, and means for guiding the movement of the front rod sections to maintain the latter in predetermined relation to the movable front wheels. 65
10. In a locomotive, a truck, front drive wheels therefor, rear drive wheels, means movably connecting the truck with the front 70 wheels and permitting swinging movement of the latter on vertical axes, pivotally connected rod sections connecting the front and rear wheels, means for guiding the rear rod sections, and means for guiding the movement of the front rod sections to maintain the latter in predetermined relation to the 75 movable front wheels.
11. In a locomotive, a truck, rear drive wheels therefor, front drive wheels, means pivotally connecting the truck with the front 80 drive wheels and permitting swinging movement of the latter on vertical axes, pivotally connected rod sections connecting the front and rear wheels, truck-carried means for guiding the movement of the rear rod sections, and means for maintaining the 85 front rod sections in predetermined relation to the movable front wheels.
12. In a locomotive, a truck, an axle supported therein, frames pivotally connected with the ends of the axle, and wheels rotatably mounted in said frames. 90
13. In a locomotive, a truck, an axle supported therein, frames pivotally connected with the ends of the axle, flanged wheels, and retainers carried by the frames and 95 engaging the flanges of the wheels to rotatably support the latter.
14. In a locomotive, a truck, an axle supported therein, frames pivotally connected with the ends of the axle, wheels, flanges 100 carried by said wheels, and substantially hook shaped retainers carried by said frames and engaging said flanges to rotatably support the wheels.
15. In a locomotive, a truck, an axle supported therein, rear wheels supporting said truck, frames pivotally connected with the ends of said axle, wheels rotatably supported in said frames, pivotally connected rod sections connecting the first and second-mentioned wheels, and means reciprocably mounted in said frames and connected with the front rod sections for guiding the movement of the latter. 105
- In testimony whereof I affix my signature 110 in presence of two witnesses.
